(57) **CLAIM**

The ornamental design for an electric hairstyling brush, as
shown and described.

DESCRIPTION

FIG. 1 is a bottom, rear and right side perspective view of
an electric hairstyling brush in accordance with the present
invention;

FIG. 2 is a partial enlarged view of the bristles of the electric
hairstyling brush of FIG. 1;

FIG. 3 is a top, front and right side perspective view of the
electric hairstyling brush of FIG. 1;

FIG. 4 is a partial enlarged view of the circular feature of the
electric hairstyling brush of FIG. 3;

FIG. 5 is a partial enlarged view of the bristles of the electric
hairstyling brush of FIG. 1;

FIG. 6 is a back elevational view of the electric hairstyling
brush of FIGS. 1 and 3;

FIG. 7 is a front elevational view of the electric hairstyling
brush of FIGS. 1-6;

FIG. 8 is a left side elevational view of the electric hair-
styling brush of FIGS. 1-7;

FIG. 9 is a partial enlarged view of the bristles of the electric
hairstyling brush of FIG. 8;

FIG. 10 is a right side elevational view of the electric
hairstyling brush of FIGS. 1-9;

FIG. 11 is a partial enlarged view of the bristles of the
electric hairstyling brush of FIG. 10;

FIG. 12 is a top plan view of the electric hairstyling brush
of FIGS. 1-11;

FIG. 13 is a partial enlarged view of the electric hairstyling
brush of FIG. 12;

FIG. 14 is a bottom plan view of the electric hairstyling
brush of FIGS. 1-13; and,

(Continued)

FIG. 15 is a partial enlarged view of the electric hairstyling brush of FIG. 14.

The broken lines in the drawings depict portions of the electric hairstyling brush that form no part of the claimed design.
